UNITED STATES PATENT OFFICE

2,283,770

SOAP AND WATER MIXER

Lucien Siano, Ballston Spa, N. Y.

Application May 24, 1941, Serial No. 395,099

1 Claim. (Cl. 299—83)

This invention relates to a soap and water mixer, and particularly to a soap and water mixer of the type disclosed in a parent application filed by me under date of February 26, 1940, Serial No. 320,980, now matured into Patent No. 2,239,021, of April 22, 1941, and entitled "Soap and water mixers."

The subject matter of the present application was divided out of my above identified application for patent, and Letters Patent, above noted, and the invention, together with the primary object thereof, namely the provision of a device of this character which may be readily connected into a flow of water, whereby the water may contact soap and become soapy so that the water leaving the device may be utilized for the washing and cleaning of various articles, automobiles or the like, or may be employed for taking baths, will be best understood from a study of the following description taken in connection with the accompanying drawing wherein:

Figure 1 is a vertical sectional view through a soap and water mixer constructed in accordance with my invention.

Figure 2 is a transverse sectional view taken substantially on the line 2—2 of Figure 1.

Referring more in detail to the drawing, it will be seen that in the embodiment illustrated, there is provided a box-like construction 5, embodying sections 6 and 7 hingedly connected, as shown at 8.

The sections 6 and 7 are held in close relationship with respect to each other by a spring clamp 9 pivoted on the section 7 and engaging with a keeper-like portion on the section 6.

The section 6 includes a water chamber 10, while the section 7 includes a water chamber 11, and a compartment 12 for containing soap S.

The compartment 12 has ports 13 to permit the escape of water from the compartment 12 into the water chamber 11 of the section 7.

The bottom wall of the section 6 is perforated, as shown at 14, to allow the water to enter the soap compartment 12.

The section 6 also includes a fitting 15 for connecting the section onto a water supply conduit as suggested in the drawing.

The section 7 includes a discharge neck in the form of a fitting, as shown at 16 for connecting the section 7 to a water conduit as illustrated.

From the above it will be seen that the water enters the chamber 10 of the device, passes into the compartment 12 to contact the soap, and from the compartment 12 passes into the water chamber 11 of the section 7 to discharge therefrom by way of the fitting 16.

It will be readily appreciated that a device of this kind can be readily connected into a hose line, wherein the hose line is provided at one end with a washing device for the cleaning of automobiles and the like, so that the water used by the washing device will contain a certain amount of soap to facilitate the thorough cleansing of the automobile, or like device.

Also, this embodiment of the invention is such that it may be readily connected into a supply pipe of a shower so that the device can be utilized for furnishing soapy water for the purpose of taking baths.

It is believed that the foregoing description, when taken in connection with the drawing, will fully set forth the construction and advantages of this invention to those skilled in the art to which such a device relates, so that further detailed description will not be required; although in this connection it may be mentioned that the device can be used to advantage for sprinkling gardens and plants and when so used, a chemical may be substituted for the soap in chamber 12.

Having thus described the invention what is claimed as new is:

A soap and water mixer of the character described comprising a pair of hinged casing sections, one of said sections being substantially 35 wedge-shaped in longitudinal section, a water inlet coupling arranged in the large end of said section, one face of said last-named section adapted to be engaged by the other of said sections and provided with a plurality of openings, 40 said second section being of substantially rectangular shape and corresponding in size to the perforated base of the first section, said second section provided with an inner spaced soap chamber open at its top and provided with a plurality of 45 water passage openings in its opposite ends, the said second section terminating in an enlarged tapered water outlet, hinge means connecting the casing sections together, and latch means for retaining the sections in fixed relation to each other.

LUCIEN SIANO.
